EGG BEATER

Filed Jan. 28, 1929

Attorney

UNITED STATES PATENT OFFICE

HENRY G. KUCK, OF PEORIA, ILLINOIS, ASSIGNOR TO STUBER & KUCK CO., OF PEORIA, ILLINOIS, A CORPORATION OF ILLINOIS

EGG BEATER

Application filed January 28, 1929. Serial No. 335,489.

This invention pertains to improvements in egg beaters, and to a method of connecting certain of the parts thereof.

Objects of the invention are to provide an egg beater that is simple in construction, thoroughly rigid and strong, and of few parts.

Further, an object is to furnish a novel manner of connecting a handle portion and beater-element supporting frame for an egg beater, which is unique in form, is sturdy and permanently rigid throughout.

Still another object is to provide a type of egg beater having a support therefor in the nature of a lid or cover for a receptacle wherein materials to be beaten are contained, the said lid or cover serving as a brace for the handle portion.

In the appended drawing—

Figure 1 is a front elevation of my complete egg beater.

Figure 2 is a side elevation of part of a handle-frame and a beater-element supporting frame portion much enlarged.

Figure 3 is a transverse section of the handle-frame portion shown in Figure 2, on line 3—3 of that figure.

Figure 4 is a transverse section of the handle-frame and beater-element supporting frame of Figure 3 on line 4—4 of that figure.

Figure 5 is a transverse section of a beater-element on line 5—5 of Figure 1, and

Figure 6 is a side elevation of the beater element shown somewhat larger than in Figure 1.

Although the drawing shows the beater in connection with a lid or cover A of a receptacle B it is also adaptable for use without said lid or cover, the structure being substantially the same in either case.

The said structure includes what I shall term a handle-frame, which, in this instance, comprises two members 1 of the same identical form. These are preferably made in channel form, or having a flange 2 at each edge as in Figures 2 and 3. At their upper ends they abut, being riveted together upon a projection 3 of a ferrule 4 receiving any usual handle 5. Below these riveted extremities the members 1 are separated to form spaced

parallel legs between which is a drive-wheel 6 of well known form having spaced openings 7, Figure 2, near its edges to engage the teeth of pinions 15 of beater-elements to be described, said wheel being supported on a crank shaft 8 journaled in said members 1.

At their lower extremities the members 1 are bent outwardly in opposite directions and then downwardly creating knee portions 9 which in this instance are riveted or otherwise suitably secured to the mentioned lid or cover A.

A frame for the usual beater elements 10 is identified by 11. This comprises a wire bent in U-form, its legs slightly converging toward their free extremities, each leg extending through and snugly fitting an opening 12 in the knee 9, Figure 2, and lying alongside the outer surface of the upright portion of said member 1. The metal of the latter, by means of a suitable die, not shown, being formed about the frame extremity into a tubular portion 13 engaging snugly said extremity, rigidly and securely holding the same, followed, if desired, by forcing portions of the said tubular portion into the extremity-walls by a suitable tool or tools, not shown.

It is noted that by this construction each leg of the beater-element supporting frame 11 is held at two spaced positions so that there can be no possibility of the said frame changing its position or form under the most vigorous use to which the device may be subjected.

Each of the said beater-elements 10 is of any usual construction and each has a bearing upon the lower end of the frame 11 in a customary way, while its upper end is affixed to the pinion 15 before referred to, said pinion being arranged to turn upon the frame 11.

Due to the type of drive for the pinions 15 practically any degree of cant may be given the legs of the frame 11, the desired divergence of the legs permitting the beater-elements to be as widely spaced as desired for free action.

The form of the handle-frame members for securing the beater-element supporting-

frame as well as the manner of forming the same about the frame extremities is believed to be novel, together with the fact that the said extremities extend through the knee portions 9 and provide for a very secure and rigid job.

While the lid or cover A provides a connection between the handle frame extremities the equivalent of the lid as a connection may be used where the beater is not to be used with a special receptacle as B but is to be portable to any receptacle wherein beating is to be done.

While I have described and shown a preferred arrangement of the egg beater it is to be understood that I do not wish to be understood as limiting myself to the exact details of construction of the same.

I claim:

1. A beater structure including a handle-frame portion having a drive wheel journaled thereon, a beater-element leg, a beater-element journaled on the leg including a pinion to engage the drive wheel, and a part for attachment thereto of said handle-frame portion, and constituting a lid or cover for a vessel to contain material to be treated, said handle-frame portion being substantially straight and paralleling the drive-wheel, the same having an outwardly extended part leading away from the said drive-wheel substantially at right angles to the plane thereof, and thence extended substantially parallel to the plane of the wheel and attached to the said lid or cover, said pinion lying in the angle of the frame thus formed, said beater-element leg extending through the outwardly extending part and held thereby, its extremity paralleling and abutting the straight portion of the frame portion and affixed thereto.

2. A beater structure including a handle-frame portion of two extensions, a drive-wheel journaled between the extensions, beater-element legs, a beater-element journaled on each of the legs each including a pinion to engage the drive-wheel, a lid or cover for a vessel to contain material to be treated, the said lid or cover being provided for attachment thereto of said handle-frame extensions, each extension being extended at right angles to the plane of the wheel away therefrom each in an opposite direction substantially parallel to the plane of said lid or cover and spaced therefrom and being extended parallel with the plane of said wheel and secured to the lid or cover, the pinions lying between the latter and the right angled extensions, said beater-element legs extending through the latter and at their extremities abutting the frame portions and affixed thereto.

In testimony whereof I affix my signature.
